UNITED STATES PATENT OFFICE

WILLIAM H. MAYER, JR., OF NEW YORK, N. Y.

DESIGN FOR A FABRIC

Application filed May 25, 1929. Serial No. 31,410. Term of patent 7 years.

To all whom it may concern:

Be it known that I, WILLIAM H. MAYER, Jr., a citizen of the United States, and a resident of the city of New York (borough of Manhattan), in the county of New York and State of New York, have invented the new, original, and ornamental Design for Fabrics, of which the following is a specification.

Reference is had to the accompanying drawing—

The figure is a plan view showing my new design for a fabric.

I claim:

The ornamental design for a fabric, as shown.

Signed at New York, in the county of New York and State of New York, this 23d day of May, 1929.

WILLIAM H. MAYER, Jr.
